UNITED STATES PATENT OFFICE

2,553,514

HEMSTITCHING ATTACHMENT FOR
SEWING MACHINESJohn P. Enos, Union, N. J., assignor to The
Singer Manufacturing Company, Elizabeth,
N. J., a corporation of New Jersey

Application August 26, 1949, Serial No. 112,443

9 Claims. (Cl. 112—160)

1

This invention relates to hemstitching attachment for sewing machines of the type disclosed in United States patent to Hinman et al., No. 2,069,652, February 2, 1937.

This invention has as its primary object to improve this type of hemstitching attachment by embodying in the attachment means to prevent the skipping of stitches due to the so-called "flagging" of the material being hemstitched.

The attachment disclosed in the above mentioned patent includes, among other elements, a feed-bar having widely spaced work-engaging portions which grip the work and shift it laterally and rearwardly and a presser-foot which bears upon the work only during the time that the feed-bar is lifted and being returned to its forward position after a rearward feeding stroke, that is, during only one of three upstrokes of the needle. During the other two upstrokes of the needle the work is held down on the work-support only by the widely spaced work-engaging portions of the feed-bar. Because of this widely spaced engagement of the work that portion of the work between the points of engagement of the feed-bar tends to pulsate with the up and down movements of the needle. This pulsation of the work is known as "flagging" and frequently prevents the casting of the needle thread loop for entrance by the point of the loop-taker. Failure of the point of the loop-taker to enter the needle thread loop results in a skipped stitch.

This invention has as an object to provide an improved presser device for hemstitching attachments which will bear upon the work adjacent the needle during each upstroke of the needle and thereby prevent upward movement of the work with the needle, thus insuring the casing of the needle thread loop and preventing the skipping of stitches.

Another object of the invention is to provide an improved presser mechanism for hemstitching attachments which will engage and bear upon the work between the work-feeding elements during each upstroke of the needle without interfering with the normal shifting and feeding of the work by the attachment.

These objects have been attained by the provision, in a hemstitching attachment of the type disclosed in the above mentioned Hinman et al. patent, of an improved presser mechanism including a main presser-foot having work-engaging and work-releasing movements in timed relation with the movements of the work-feeding mechanism and an auxiliary presser-foot having work-engaging and work releasing movements in

2

timed relation with the reciprocations of the machine needle.

With the above and other objects in view, as will hereinafter appear, the invention comprises the devices, combinations and arrangements of parts hereinafter set forth and illustrated in the accompanying drawings of a preferred embodiment of the invention from which the several features of the invention and the advantages attained thereby will be readily understood by those skilled in the art.

In the drawings,

Fig. 1 is a transverse vertical section of a portion of a conventional lock-stitch sewing machine having my improved hemstitching attachment applied thereto, showing the attachment in side elevation.

Fig. 2 is a front view of a portion of the sewing machine shown in Fig. 1, showing the front end of the improved hemstitching attachment.

Fig. 3 is a horizontal section taken substantially on the line 3—3 of Fig. 1 and showing the attachment in plan view.

Fig. 4 is an under side view of the attachment with a portion thereof broken away.

Fig. 5 is a detail side elevation of portions of the improved attachment showing the relationship between the needle, the feed-plate, and the main and auxiliary presser-feet.

Fig. 6 is a view similar to Fig. 5 but with the parts in different positions.

Fig. 7 is a longitudinal sectional view through the attachment.

Fig. 8 is a detail perspective view of a portion of the main frame of the attachment and the main presser-foot forming a part thereof.

Fig. 9 is a detail perspective view of the auxiliary presser-foot and its supporting lever.

Referring more specifically to the drawings, the improved attachment is shown as applied

40 to a sewing machine having a frame including a work-supporting plate 1, a bracket arm (not shown) terminating in a head 2 in which is mounted a reciprocating needle-bar 3 to which is secured, by a needle-clamp 4, an eye-pointed thread-carrying needle 5. Also mounted in the head 2 is a spring-depressed presser-bar 6 which, when the machine is used for straightaway sewing, carries the usual presser-foot, not shown.

When the machine is to be used for hemstitching the presser-foot is removed and the hemstitch attachment is secured to the presser-bar as, for example, by screw 7 (see Fig. 3).

The machine is also provided with a conventional four-motioned work feeding mechanism

including a feed-bar 8 carrying a feed-dog 9, a feed-drive mechanism designated generally as 10 and a feed-lift mechanism 11. In normal straightaway sewing the teeth of the feed-dog operate through slots formed in a throat-plate (not shown) which fits into a cavity 12 formed in the upper face of the work-supporting plate 1. When the machine is used for hemstitching the throat plate is removed from the machine and there is secured to the upper face of the work plate an improved feed cover plate, designated generally as 13 which supports the work and holds it out of contact with the feed-dog 9, which therefore may partake of its usual four motions without effecting the work. This improved feed-cover plate forms no part of the present invention but is the subject of my United States patent application Serial No. 112,442, filed August 26, 1949.

Cooperating with the needle in the formation of stitches is a conventional rotary hook shown only in dotted lines in Fig. 1 and designated generally as 14. As is customary with this type of stitch-forming mechanism this rotary hook carries a mass of under thread and is formed with a beak which enters the thread-loop cast out by the upward movement of the needle and expands that loop and passes the mass of under thread therethrough, thereby forming a conventional lock stitch. Failure of the beak to enter, the needle thread loop results in a skipped stitch, as is well understood.

The present improved hemstitch attachment which, as hereinbefore stated is generally similar to the hemstitch attachment disclosed in the Hinman et al. Patent No. 2,069,652, comprises a main frame including a horizontal bottom plate 15 and upstanding side walls 16 and 17 which afford journals for a step-by-step rotatable shaft 18 later to be described. The side wall 16 is formed with an offset vertically disposed U-shaped portion 19 designed to embrace the presser-bar 6 and to be secured thereto by the before mentioned screw 7.

Rotatably journaled on the shaft 18 exteriorly of the side wall 16 is the hub 20^a of an actuating lever 20 which has its free end bifurcated at 20^b to straddle a stud 4^a carried by the needle-clamp 4. Thus the lever 20 is oscillated on the shaft 18 by the up and down reciprocations of the needle-bar 3. The lever 20 carries a spring pressed pawl 21 the free end of which engages the teeth of a ratchet wheel 22 fixed upon the shaft 18. Through the lever 20 and the pawl 21 and the ratchet wheel 22 the shaft 18 is given step-by-step rotary movements.

Slidably mounted at the under side of the frame plate 15 for sidewise work shifting and endwise work feeding movements is a feed-plate 23 having, on its under side and rearwardly of the stitching point, a serrated work-feeding portion 24. The feed-plate 23 also carries, at its forward end, space spring fingers 25 and 26 provided with serrated surfaces 27 and 28 respectively, which engage the work and shift it laterally and rearwardly during the hemstitching operation.

As shown most clearly in Figs. 7 and 8, the bottom plate 15 of the attachment frame is provided at its forward end with a main presser-foot 29 which, at certain times bears upon the work at one side of the stitching point. This presser-foot is formed with an aperture or notch 30 to permit passage of piercer point P forming a part of a work-piercing mechanism designated generally as P. This piercer mechanism is con-

structed and actuated substantially the same as in above mentioned Hinman et al. No. 2,069,652. Inasmuch as this piercer mechanism forms no part of this invention detailed illustration and description thereof is deemed unnecessary. Suffice it to say that it is actuated by reciprocation of the needle-bar and by a cam 31, in the form of a star wheel, secured upon the shaft 18, as in the Hinman et al. patent.

The feed-plate 23 is slidably pivoted, at its rear end, to the plate 15 by a stud 32 and is normally urged forwardly and upwardly by a coil spring 33 having one end connected to a lug 67 projecting upwardly from the plate 23 and its opposite end connected to a stud 5 carried by the frame side wall 16. The feed-plate is shifted rearwardly, in opposition to the spring 33, to give the work its advancing movement, by a cam wheel 34 secured to rotate with the shaft 18, a cooperating two-armed lever 73, pivoted at 74 to the frame side wall 17, and an abutment member 69 on the feed-plate as in said Hinman et al. patent. Lateral work-shifting movements are given to the feed-plate 23 by laterally offset cam surfaces 79 formed on a cam disk 35 rotatable with the shaft 18. The cam surfaces 79 operate between vertically disposed lugs 67, 68 pressed upwardly from the feed-plate 23.

The disk 35 is formed on its periphery with four cam surfaces 77 and four concentric surfaces or dwells 77^a which operate successively on the upper surface of the feed-plate 23 as shown most clearly in Fig. 7. The surfaces 77 and 77^a are connected by an abrupt shoulder 78. Under the urge of the spring 33 the upper surface of the feed-plate is constantly pressed against the periphery of the disk 35. Adjacent the intermediate portion of the feed-plate 23 and slightly to one side of a vertical plane containing the axis of the shaft 18 the metal of the plate is displaced downwardly, as shown at 62, to provide a recess 63 into which drops at certain times, the concentric portion of the cam disk 35 adjacent the shoulder 78 thereby permitting the feed plate to be raised by the spring 33. As the disk is turned from this point, the cam surface 77 of the disk 35 forces the feed plate downwardly to cause the serrated portions 24, 27 and 28 to bear upon and grip the work supported by the feed cover plate 13. After the work has been firmly gripped and further lowering of the feed plate is precluded, further action of the cam surface 77 on the feed plate causes the entire attachment exclusive of the feed-plate 23 to be raised. This action lifts the main presser-foot 29 above the work and permits the sidewise and endwise movements of the feed plate to give to the work the required movements to produce hemstitching. The concentric portion 77^a of the disk maintains the feed-plate depressed until after the three-stitch hemstitch cycle has been completed and the work has been fed toward the rear of the machine. At the completion of this feeding stroke the shoulder 78 is aligned with the recess 63 thus permitting the attachment frame and the presser-foot 29 carried thereby to be lowered under the influence of the presser-bar spring and also permitting the feed-plate 23 to be raised by the spring 33 and to be shifted forwardly thereby as soon as one of the high points 81 of the cam wheel 34 has been rotated out of contact with the lever 73.

From the foregoing it will be understood that the main presser-foot 29 bears upon the work during the forward return of the feed-plate 23

and during only one of each three upstrokes of the needle in a three-stitch hemstitch cycle. During the other two upstrokes of the needle the feeding portions 24, 27 and 28 of the feed-plate 23 bear upon the work and the presser-foot 29 is maintained above and out of contact with the work.

Heretofore it has been during these two upstrokes of the needle, i. e. when the work was held downward only by the widely spaced feeding portions 24, 27 and 28 of the feed-plate, that the portion of the work in the region of the needle tended to "flag," which frequently caused the skipping of stitches as hereinbefore explained.

This invention has provided an auxiliary presser device which is actuated in timed relation with the reciprocations of the needle and which includes a foot adapted to bear upon the work adjacent the needle at each upstroke thereof, thereby positively to preclude "flagging" of the work and the consequent skipping of stitches.

This auxiliary presser device comprises a horizontally disposed presser lever 36 fulcrumed, intermediate its ends, upon a shoulder screw 37 threaded into an aperture 38 in the frame side wall 16. The front end of the lever 36 has a laterally offset portion 36^a to the downturned end of which is pivotally mounted an auxiliary presser-foot 39. The auxiliary presser-foot is located at the side of the needle opposite to the main presser-foot and has a toe portion 39^a which extends forwardly beyond the toe of the main presser-foot. The auxiliary presser-foot also has a heel portion 40 provided with a thread-clearance aperture 41 rearwardly of the path of reciprocation of the needle.

The rear half of the presser lever 36 is cut away as at 36^b to avoid interference with the ratchet wheel 22 and is provided with an end portion 36^c adapted to be engaged by a cam 42 formed on the hub 20^a of the actuating lever 20. A spring 43 surrounding a screw 44 and having one leg engaging the side wall 16 and another leg engaging beneath the rear half of the lever 36 normally urges the lever counterclockwise as viewed in Fig. 1, thereby tending to depress the auxiliary presser-foot 39 into contact with the work, designated as W in Figs. 5 and 6.

In Fig. 5 the needle-bar 3, needle 5 and the lever 20 are shown in full lines in their lowermost positions. In this position the cam 42 on the hub of the lever 20 is spaced angularly from the portion 36^c of the lever 36. As the parts move from the position shown in full lines to the position illustrated in dotted lines the cam portion 42 has no effect on the lever 36 and therefore the auxiliary presser-foot 39 remains in pressure contact with the work. It is during this interval that the needle has its initial upward movement which casts out the needle-thread loop for entrance by the beak of the loop-taker. After the needle-loop has been seized by the loop taker the needle-bar and the lever 20 have a further upward movement which causes the cam 42 to engage the rear end of the lever 36 thereby turning that lever clockwise (Fig. 1) and lifting the auxiliary presser-foot 39 off the work to permit the work to be shifted by the feed plate 23.

From the foregoing it will be understood that the main presser-foot 29 cooperates with the work-feeding elements 24, 27 and 28 on the feed-plate 23 to hold the work stationary during the time that the feed-plate is out of contact with the work. Also, that the movements of the auxiliary presser-foot 39 are so timed with the re-

ciprocations of the needle-bar and needle as to hold the work against "flagging" during each initial upstroke of the needle and to be lifted off the work during each lateral and rearward movement of the work by the feed-plate 23.

Having thus set forth the nature of the invention, what I claim herein is:

1. A hemstitching attachment for a sewing machine having a reciprocating needle, including a feed-plate adapted to engage and feed the work rearwardly of the machine and laterally of the line of seam formation in two directions, means operative after each complete feeding cycle for raising said feed-plate out of contact with the work, means to shift said feed-plate forwardly while it is out of contact with the work, a main presser-foot constructed and arranged to bear on the work during the time that the feed-plate is out of contact with the work, and an auxiliary presser-foot actuated in timed relation with the reciprocations of the needle and designed to bear upon the work during each upstroke of the needle.

2. A hemstitching attachment for a sewing machine having a reciprocating needle-bar and a needle carried thereby, including a feed-plate having sidewise and endwise movements adapted to engage and feed the work laterally and rearwardly of the machine in a predetermined three-stitch cycle, means operative after each third stitch for raising said feed-plate out of contact with the work to permit it to be shifted forwardly preparatory to the beginning of a new feeding cycle, a main presser-foot constructed and arranged to bear upon the work during the time that the feed-plate is out of contact with the work, and a vertically movable auxiliary presser-foot actuated by the reciprocations of the needle-bar and designed to bear upon the work during each upstroke of the needle.

3. A hemstitching attachment for a sewing machine having a reciprocating needle-bar, and a thread-carrying needle carried thereby, including a frame, a feed-plate carried by said frame and adapted to engage and feed the work, an actuating lever fulcrumed on said frame and operated by the reciprocations of said needle-bar, means actuated by said lever for periodically raising said feed-plate out of contact with the work, a main presser-foot secured to said frame, said presser-foot being constructed and arranged to bear on the work during the time that the feed-plate is out of contact with the work, and an auxiliary presser-foot fulcrumed on said frame and designed to bear upon the work during each upstroke of the needle.

4. A hemstitching attachment for a sewing machine having a reciprocating needle, including a feed-plate adapted to engage and feed the work, means periodically raising said feed-plate out of contact with the work, a vertically movable main presser-foot constructed and arranged to bear on the work during the time that the feed-plate is out of contact with the work, and an auxiliary presser-foot designed to bear upon the work adjacent the needle during the initial portion of each upstroke of the needle.

5. A hemstitching attachment for a sewing machine having a reciprocating needle-bar and a thread-carrying needle carried thereby, comprising a frame, an actuating lever fulcrumed on said frame and operated by the reciprocations of said needle-bar, a presser-lever fulcrumed on said frame, a presser-foot carried by said presser-lever and designed to bear upon the work adja-

cent said needle, spring means normally biasing said presser-lever to a position to cause said presser-foot to bear upon the work, and a member carried by said actuating lever and acting on said presser-lever to lift said presser-foot from the work in opposition to said spring means after the needle-bar has been lifted sufficiently to cause the needle to cast its thread loop.

6. A hemstitching attachment for a sewing machine having a reciprocating needle-bar and a thread-carrying needle carried thereby, comprising a frame, an actuating lever fulcrumed on said frame and operated by the reciprocations of said needle-bar, a horizontally disposed presser-lever fulcrumed intermediate its ends on said frame, a presser-foot carried by one end of said presser-lever and designed to bear upon the work adjacent said needle, spring means normally biasing said presser-lever to a position to cause said presser-foot to bear upon the work, and a cam member carried by said actuating lever and acting on the other end of said presser-lever during each upstroke of the needle-bar to lift said presser-foot from the work in opposition to said spring means after the needle-bar has been lifted sufficiently to cause the needle to form a thread loop.

7. A hemstitching attachment for a sewing machine having a reciprocating needle-bar and a thread-carrying needle carried thereby, comprising a frame, an actuating lever fulcrumed on said frame and operated by the reciprocations of said needle-bar, a presser-lever fulcrumed on said frame, a presser-foot carried by said presser-lever and designed to bear upon the work adjacent said needle, spring means normally biasing said presser-lever to a position to cause said presser-foot to bear upon the work, and a cam carried by said actuating lever and acting on said presser-lever to lift said presser-foot from the work in opposition to said spring means, there being sufficient lost motion between said cam and said lever to delay the movement of

5
10
15

the lever and the presser-foot carried thereby until the needle-bar has been lifted sufficiently to cause the needle to cast a thread loop.

8. A hemstitching attachment for a sewing machine having a vertically reciprocating thread-carrying needle, including a vertically and horizontally movable feed-plate adapted to engage and feed the work, a main presser-foot constructed and arranged to bear upon the work when the feed-plate is elevated, and a vertically movable auxiliary presser-foot actuated in timed relation with the reciprocations of said needle, said auxiliary presser-foot being constructed and arranged to bear upon the work adjacent the needle during the initial portion of each upstroke of the needle to prevent flagging of the work during the casting of the needle-thread loop.

9. A hemstitching attachment for a sewing machine having a reciprocating needle-bar and a needle carried thereby, including a feed-plate, means to give to said feed-plate sidewise and endwise movements to feed a work-piece laterally in two directions and thence rearwardly of the machine in each complete feeding cycle, means operative after the completion of each feeding cycle for raising said feed-plate out of contact with the work to permit the feed-plate to be shifted forwardly preparatory to the beginning of a new feeding cycle, and a vertically movable presser-foot actuated by the reciprocations of the needle-bar and designed to bear upon the work during each upstroke of the needle.
